(57) **CLAIM**

The ornamental design for a shower chair seat, as shown and described.

DESCRIPTION

FIG. 1 is a perspective view of our new design for a shower chair seat.

FIG. 2 is a top plan view.

FIG. 3 is a bottom plan view.

FIG. 4 is a right side elevation view.

FIG. 5 is a rear elevation view.

FIG. 6 is a left side elevation view; and,

FIG. 7 is a front elevation view.

The broken lines shown in the drawing are for illustrative purposes only and form no part of the claimed design.
